UNITED STATES PATENT OFFICE.

CHARLES HENRY JARRETT, OF CROYDON, ENGLAND.

ADVERTISING AND LIKE DEVICE.

Application filed January 21, 1926, Serial No. 82,777, and in Great Britain January 31, 1925.

This invention relates to improvements in advertising and like devices of the type in which a stencil having the advertising or like matter formed therein revolves around a source of illumination. The chief object of my invention is to obtain sharp definition of the advertising or like matter of the stencil. Further objects of my invention are to enable the stencils to be changed with rapidity and ease, and to provide a screen for the reception of the advertising or like matter projected from the stencil, which gives the appearance of a constantly revolving sphere. By "sharp definition" I mean the absence of blurring of the projected matter, as seen by the normal eye.

According to this invention, the rays from the lamp or the like for projection of the advertising or like matter are focussed within the stencil so as to produce sharp definition. The focussing of the light is effected preferably by means of an aperture formed in a casing applied to or surrounding the lamp. It may, however, in some cases be obtained by using a very small light source.

The stencil is constructed independently of its upper supporting portion so that it can be readily changed for a fresh stencil.

According to a further feature of this invention, the screen on to which the light from the said source of illumination is projected may be hemi-spherical, or substantially so, and translucent.

According to a still further feature of this invention, the source of illumination may be so arranged that it illuminates the space behind the device as well as displaying the advertising matter.

Other advantages and novel features of this invention will be described hereinafter and claimed in the appended claims.

In the drawings, which illustrate the preferred embodiments of this invention

Figure 1 is an elevation of the complete apparatus.

Figure 2 is a central vertical section of the same.

Figure 3 is a plan on an enlarged scale of the bearing for the stencil.

Figure 4 is a section of the said bearing attached to the stencil-support.

Figure 5 is a front elevation of a stencil.

Figure 6 is an elevation of the lamp holder in the open position.

Figure 7 is a central vertical section of a further form of this invention, and

Figure 8 is a front elevation of the lamp and screen therefor.

Referring to Figures 1 to 6 of the accompanying drawings, the main parts of the device are fitted to an ornamental wooden frame or stand *a* which can be hung up on a slotted plate *a*¹ or can be arranged to stand by means of two back stays *a*² which are hinged to the back of the stand *a*. Feet *a*³ are preferably provided at the bottom of the frame *a* and are of such length that the front of the frame slopes backwardly, as shown in Figure 2.

The source of illumination and of the heat required to rotate or drive the stencil is an electric lamp *b* of the ordinary single filament "strip" or show-case type, or in other words a lamp which is of the long tubular type.

The lamp holder *b*¹ is tubular in shape and made of tin or any other suitable material. The lower portion of the lamp holder is made in such a way as to serve as a reflector which is of such shape and so arranged as to reflect the light of the lower part of the lamp backwards into the shop window or the like in which the device is placed, (see Figures 2 and 6).

At a suitable distance up the lamp holder is cut an aperture *b*² preferably in the form of a horizontal slot, the said slot being so situated or arranged that the exposed portion of the lamp filament *b*³ is approximately at the centre of the hemi-sphere or other type of screen, *c*, being used. The lamp holder therefore serves as a mask between the source of light and the stencil. The inside of the upper part of the lamp holder *b*¹ is blackened as at *b*⁴ to prevent reflection within the holder. The back *b*⁴ of the top half of the lamp holder *b*¹ is hinged to allow for the "strip" lamp *b* to be easily fitted into and removed from the holder.

In some cases, the lamp holder *b*¹ can be in skeleton form,—only sufficient of it being retained to hold the lamp in position or the lamp may be fixed by any other suitable method, in which case the lamp *b* itself would be screened, masked, blackened or otherwise suitably treated so as only to leave the desired small aperture, corresponding to the aperture *b*², and the lower rear portion of the lamp, clear.

The lamp *b* is preferably held in the holder by a spring *b*⁵ which is situated at the bottom of the holder *b*¹ and which, by

its pressure, presses the lamp *b* against the top end of the lamp holder *b*¹. The said spring *b*⁵ is preferably housed within a casting or sleeve *b*⁶. The electric wires *d* are connected to small caps *d*¹ which are made of teak-wood or other suitable non-conducting material. The said caps *d*¹ are made to fit easily on each end of the lamp, and the wires are connected to the caps by small screws *d*², the points of the screws being caused to make contact with the lamp *b* and the screws being let into the caps *d*¹ in such a manner that perfect insulation is secured.

15 The pivot (see Figures 2 and 4) consists of a steel or other point *e*, and is suitably supported at the top of the lamp holder or mask *b*¹ between the latter and the screen *c*. Conveniently, the pivot point *e* is carried by 20 a member *e*¹ slidable in an eye or the like *b*⁷, on the top of the lamp holder *b*¹. The said pivot point is preferably carried in a central hole in a rod *e*² which screws through the slidable member *e*¹ and so the 25 height of the stencil with respect to the lamp may be varied. When the lamp holder *b*¹ described above is not used the pivot *e* above mentioned can be fixed in any other suitable manner.

30 The stencil *f* (Figures 2 and 5), which may comprise a cylinder having spaces *f*¹ cut out in any manner to represent letters, figures, words or any other designs, has at its upper end an inwardly turned flange *f*² which rests on a disc *f*³ provided with vanes *f*⁴ on which the heated air impinges and causes the stencil *f* to revolve. A central cup-shaped bearing *f*⁵ is fixed in the centre of the vanes *f*⁴ to receive the point of the 40 pivot *e*. The said cup-shaped bearing *f*⁵ is preferably hollow and made of glass although it may, if so desired, be made of any other suitable material. The said bearing is secured to the vanes by means of a 45 collar *f*⁶ which takes over the upper tubular portion *f*⁷ of the said bearing and is provided with radial lugs *f*⁸, conveniently three in number, which are bent over the outside of the bearing, are passed through the disc *f*³ and are clinched over on the under side thereof. By having the pivot point of steel and pivot cup bearing of glass, friction and wear are reduced to a minimum.

55 The vanes and the bearing constitute a single unit separate from the cylinder. Thus, by lifting the cylinder off the disc *f*³ one cylinder can be changed for another in order to change the wording etc., of the advertisement, the same vanes and bearing 60 serving for all the cylinders. In this way, the advertisement can be changed from time to time with the minimum of labour—rendering the advertisement always new—the only cost being that of the cylinders which 65 is very small indeed.

Since the pivot *e* is between the lamp holder or mask *b*¹ and the screen *c*, the axis of rotation of the cylindrical stencil *b* is eccentric to the source of light and there accordingly is sufficient space between the 70 apertured side of the lamp holder or mask and the cylindrical stencil to permit illumination of the interior of the stencil from its upper to its lower edge so that a cylindrical stencil of smaller diameter can be 75 used than would be necessary if the axis of rotation of said stencil were concentric with the source of light.

Instead of the advertising matter being cut out of the stencil *f*, the stencil may itself be of transparent material and may have the advertising matter painted on or otherwise applied thereto.

The outer screen *c* is fixed or held by a ring *c*¹ or other shaped carrier or frame 85 which is of brass or other suitable material and is mounted in position on the stand *a* by a hinge *c*² and by clipping under a screw head *c*³; or it may be mounted in any other suitable way so that it can be easily detached to allow of the screen being changed when necessary. An inner ring *c*⁴ is provided so that the glass or like screen *c* may be held firmly.

The screen above mentioned may be made of celluloid, glass, paper or any other suitable translucent material, and the ring or frame containing the screen may be fixed in any suitable manner on to the outer frame or stand or, in some cases, to a show-card.

A forwardly extending hood *a*¹ is provided on the stand *a* to prevent light rays passing upwardly through the vanes on to the screen *c*.

When the apparatus is assembled and is in operation, the only parts seen from the front are, as illustrated in Figure 1, the screen *c* with the lettering or designs *c*⁵ appearing and disappearing thereon due to the rotation of the stencil.

A cover *g* of suitable design is secured to the back of the stand *a* so as to protect the working parts of the device.

Referring now to Figures 7 and 8 of the accompanying drawings. The device is of 115 substantially the same construction comprising the framework *a* provided with a heavy counter-weight *a*⁵ which is secured to the framework *a* by means of rods *a*⁶, the counter-weight constituting a foot to hold the 120 device upright. The lamp holder *h* is mounted on a bracket *h*¹ secured to the framework *a*. The lamp *h*² is a standard projector lamp and is arranged so that its filament *h*³ is edge-on to the screen *c* as seen 125 directly from the front of the apparatus as shown clearly in Figure 8. The lamp is partially surrounded and so masked by a screen *j* provided with an aperture *j*¹ through which the light rays for the projec- 130

tion of the advertising matter may pass. The screen *j* carries the adjustable pivot pin as in the construction illustrated by Figures 1-6. The stencil *f* is constructed 5 separate from the vane disc *f*⁸ which are provided with a central agate or sapphire bearing *f*⁹. The vanes *f*¹⁰ may be surrounded by a small chimney *f*¹¹ to increase the draught. Also a plate *a*⁷ is provided to 10 prevent the light rays passing downwardly on to the lowermost portion of the screen *c*.

In a device constructed in accordance with this invention, the beam of light passing through the said aperture produces, on 15 the screen, a sharply defined and magnified projection of the letters *f*¹, etc., in the stencil or cylinder *f*, the size of the projected letters *c*⁵ being determined by the distance between the screen *c* and the stencil or cylinder *f*. Due to the magnification a comparatively large number of words, sentences, or other advertising matter etc., can be cut 20 in the stencil or cylinder and made to appear on the screen in such a size that it 25 can be read with ease at a distance.

If desired, a flat or other shaped screen may be used instead of a hemi-spherical shaped screen *c*. When a flat screen is employed the letters, etc. will diminish in size 30 from one end towards the middle of the screen and then increase in size as they travel to the other end of the screen.

Any other desired form of illumination and heat may be used, if so desired, for example, an oil or gas lamp may be employed. Also, more than one lamp may be employed, if so desired.

The shape of the lamp holder and lamp may be varied, more particularly in large 40 signs, or when the illumination from the lower half of the lamp is not required. In large signs it would be necessary to use a more powerful electric or other lamp, for example, a 400 to 500 watt lamp.

45 Thus it will be obvious that the lamp holder can be made in any way and to any design, providing only that the required aperture for the purpose of focussing the light is obtained.

50 In order to vary the colours of the light projected on to the screen, means may be provided for enabling differently coloured pieces of glass *h* or the like to be interposed between the light-source *h*² and the stencilled cylinder *f*. Such means may comprise a grooved holder *l* into which the different glasses or the like can be placed. In order to produce a striped effect, I may use glass 55 striped with different colours arranged vertically. By turning this striped glass so that the stripes are horizontal the colouring remains stationary. Instead of employing coloured pieces of glass to vary the colour of the projected light, the revolving cylinder or stencil may be covered with coloured

transparent material in any suitable manner to secure the required colours. Or in some cases the outer screen may be coloured and may even be painted with various designs to aid the advertising matter, if so desired. 70

Large outdoor signs constructed in accordance with this invention possess a great advantage over other signs which employ a large number of lamps in that a large illuminated advertisement can be obtained by 75 the use of a very small light-source, whereby only a small consumption of current, or other medium from which the light is obtained is necessary. In the case more particularly of large advertisements, the screen 80 may be semi-cylindrical or cylindrical.

When the advertising device is placed in an exposed position or is liable to be subjected to wind or other air currents, the stencil may be driven by a motor geared to a toothed ring on the stencil or otherwise in operative connection with the stencil. In such a case, the bearing above described may be replaced by a ball, roller or other suitable bearing. 85

It will be appreciated that many types of lamps are suitable for use in an advertising device according to this invention. The sharp definition which it is the chief object of this invention to obtain, may be secured by means of an automobile lamp which may be worked from accumulator or from A. C. mains by means of a transformer, or by means of a standard projector type lamp with the filament "edge-on" as described in connection with Figures 7 and 8. Further, 90 it may if desired be a Point-o'-Light lamp or a tungsten arc lamp. In fact, any lamp which will give the desired point of light or a perpendicular line of light may be employed. I have found that it is desirable 95 that such line of light should not be more than $\frac{1}{2}$ inch long, and that if the filament of the lamp which it is desired to employ is of greater dimensions it should be suitably masked or screened for example as described 100 with reference to Figure 1-6. Or the source of light within the stencil may be focussed to suitable dimensions by optical means, for example, by means of a lens or lenses or by 105 means of a concave mirror. 110

The screen may, in some cases, be dispensed with and the light rays after passing through the stencil may be arranged to impinge on the window of a shop or the like. 115

I claim:—

1. An advertising device comprising a lamp, a lamp holder in two parts hinged together, the one part being shorter than, and arranged to close upon, the upper portion of the other part, the longer part of the lamp holder having a horizontal slot, the inside portion of the shorter part and the upper portion of the inside of the longer part being blackened to prevent internal reflections and the lower portion of the longer part 120 125 130

being bright to reflect the light from said lower portion backwardly, a pivot point carried by the upper portion of the lamp holder, a cylindrical stencil rotatably supported on said pivot point about the lamp and a translucent screen for displaying the advertising matter on an enlarged scale.

2. An advertising device comprising a lamp, a lamp holder in two parts hinged together, the one part being shorter than, and arranged to close upon the upper portion of the other part, the longer part of the lamp holder having a horizontal slot, the inside portion of the shorter part and the upper portion of the inside of the longer part being blackened to prevent internal reflections and the lower portion of the longer part being bright to reflect the light from said lower portion backwardly, a pivot point adjustably carried by the upper portion of the lamp holder, a cylindrical stencil rotatably supported on said pivot point about the lamp, and a hemi-spherical translucent screen for displaying the advertising matter on an enlarged scale.

3. An advertising device comprising a lamp, a lamp holder in two parts hinged together, the one part being shorter than and arranged to close upon the upper portion of the other part, the longer part of the lamp holder having a horizontal slot, the inside portion of the shorter part and the upper portion of the inside of the longer part being blackened to prevent internal reflections, and the lower portion of the longer part being bright to reflect the light from the lower portion of the filament of the lamp backwardly, a pivot point adjustably carried by the upper portion of the lamp holder, a cylindrical stencil rotatably supported on said pivot point about the lamp, a coloured glass interposed between the lamp holder and said stencil to colour the projected light and a hemi-spherical translucent screen for displaying the advertising matter on an enlarged scale.

4. A device of the class described, comprising a translucent substantially hemispherical screen, a source of light and a mask for said source of light behind said screen, said mask having an aperture for the passage of rays of light from said source of light against said screen, a pivot supported by said mask

between said mask and screen, and a cylindrical stencil supported by said pivot for rotation on its longitudinal axis around said source of light and mask.

5. A device of the class described, comprising a translucent screen, a source of light behind said screen, a mask between said source of light and said screen and having an aperture for the passage of rays of light from said source of light against said screen, a vertical spindle carried by said mask on the opposite side thereof from said source of light, and a cylindrical stencil surrounding said source of light and said mask and supported by said spindle for rotation on its longitudinal axis.

6. A device of the class described, comprising a translucent screen, a source of light behind said screen, a mask between said source of light and said screen and having an aperture for the passage of rays of light from said source of light against said screen, a bracket projecting from said mask above said aperture toward said screen, a vertical spindle carried by said bracket, and a cylindrical stencil surrounding said source of light and said mask and supported by said spindle for rotation on its longitudinal axis.

7. A device according to claim 6 wherein the spindle-supporting bracket is horizontally adjustable.

8. A device of the class described, comprising a translucent screen, a source of light behind said screen, a mask between said source of light and said screen and having an aperture for the passage of light rays from said source of light against said screen, a bracket mounted on said screen above said aperture and extending toward said screen, a rotatable bearing element supported by said bracket above said mask, and a cylindrical stencil surrounding said source of light and said mask and detachably supported by said bearing element.

9. A device according to claim 8 wherein the bearing element carries a disc and the cylindrical stencil has means projecting from its internal periphery and resting upon said disc.

In testimony whereof I have signed my name to this specification.

CHARLES HENRY JARRETT.
